ELECTRIC SWITCH

Herbert O. Wilson, Livingston, N. J., assignor to
 Thomas A. Edison, Incorporated, West Orange,
 N. J., a corporation of New Jersey

Application October 30, 1936, Serial No. 108,420

11 Claims. (CL 200—87)

This invention relates to electric switches, and more particularly to switches which are electro-magnetically thrown and/or maintained in thrown condition.

The invention especially, though in certain aspects non-limitatively, contemplates devices of the class described in the form of vacuum switches or relays. By vacuum switches or relays are meant to be included current-making and breaking devices of which at least the active contacts or equivalent are enclosed in a sealed container or envelope which is evacuated of air for well understood purposes; optionally an atmosphere of inert gas may be provided within the envelope for one or another special purpose known in the art, without altering the nature of the device as a vacuum switch (or relay) for purposes of present consideration.

In connection with vacuum switches or relays, my invention has special reference to those wherein a controlling magnetic field is generated externally of the envelope; for several practical reasons—for example, difficulty in properly degassing relay coils or the like included within the envelope, envelope size, etc.—such devices have been generally preferred in the art. But limitations in performance—e. g., in sensitivity and in speed, abruptness and positiveness of action—have tended strongly to limit the utility of such devices; and my invention is directed among other things to the circumvention or minimization of these limitations.

Thus it is an object of my invention to provide a device of the class last described which is characterized by one or more or all of the characteristics of high sensitivity and speed, abruptness and positiveness of operation.

It is a broader object to provide an electromagnetic vacuum switch similarly characterized.

It is another object to provide an electromagnetic vacuum relay which may at the same time be small, compact and highly sensitive.

It is another object to provide a generally improved electromagnetic switch.

It is another object to maintain abruptness and positiveness of operation at both extremities of the range of movement of the movable elements of an electromagnetic switch.

It is still another object to provide an improved magnetic circuit for a magnetic switch—i. e., one responsive to a magnetic field.

A more specific object is the tightening of effective coupling between an envelope-enclosed magnetic circuit and an external means arranged

to energize that circuit, and the provision of improved means therefor.

Other and allied objects will more fully appear from the following description and the appended claims.

In the detailed description of my invention hereinafter set forth reference is had to the accompanying drawing, of which:

Figure 1 is a view, generally cross-sectional but principally elevational as to components within the envelope and diagrammatic as to certain external circuit elements, of a vacuum switch or relay embodying my invention;

Figure 2 is a cross-sectional view taken along the line 2—2 of Figure 1;

Figure 3 is a partial plan view looking downwardly from the spring 17 and armature 16 of Figure 1;

Figure 3a is a right-hand end view of the pole member 11 of Figure 1, showing the shading ring 43 in place thereon;

Figure 4 is a view, of similar nature to Figure 1, but illustrating a modified vacuum switch or relay embodying my invention;

Figure 5 is a partial cross-sectional view taken along the line 5—5 of Figure 4;

Figure 6 is a view, of similar nature to Figure 1, but illustrating a further modified vacuum switch or relay embodying my invention; and

Figure 7 is a partial cross-sectional view taken along the line 7—7 of Figure 6.

In Figures 1 and 2 I have illustrated a switch or relay arranged with a thermal element to provide a predetermined time interval between the inception of current supply to the switch and the throwing of the switch, and arranged with electromagnetic means for maintaining the switch thrown during the continuance of current supply—this maintenance by the electromagnetic means permitting the cooling of the thermal element to re-condition the device for proper quickly-repeated operation should that be desired. Several features of this switch cooperate to produce a device having high sensitivity and other desirable characteristics; and in describing the device I shall first consider the armature and core system, secondly the balance of the magnetic structure, and thirdly the general organization of the device.

In Figures 1 and 2 will be seen the elongated evacuated envelope 1, provided at one of its extremities with the seal 2, through which seal pass a plurality of lead-in wires, shown as the three wires 3, 4 and 5, hereinafter referred to. Longitudinally within the envelope, for example

near one side thereof in manner hereinafter more detailedly described, is supported a magnetic core system comprising two pole members 11 and 12 of magnetic material such as iron, and for example of rectangular cross-section (transversely of the envelope). The pole members are serially arranged and longitudinally spaced apart to form a small gap 13 between their mutually exposed respective ends or faces 21 and 22; it is convenient to hold them in the specified relationship by a flat, non-magnetic plate 14 secured to the bottom of each. Near the gap 13 and toward the center of the device therefrom I provide a flexibly supported armature 16 of magnetic material; this may be relatively short (i. e., longitudinally of the envelope), and of a rectangular cross-section (i. e., transversely of the envelope) of the order of that of the pole members. The flexible support of the armature is one which permits movement toward and away from the gap transversely of the envelope, and is desirably a resilient one; it may be provided by securing the armature to the core system side of a light leaf spring 17, preferably of non-magnetic material such as phosphor bronze or beryllium copper. This spring is conveniently extended toward the seal 2 to be clamped in the usual insulating stack or washer assembly 18, which may be secured to the pole member 11. The armature is biased away from the gap, as by suitable tensioning of the spring 17; but it is limitedly biased, in that its movement away from the gap is restricted (by means hereinafter apparent) to the originally mentioned nearby position. A system of contacts is associated with the armature in suitable manner, such as that hereinafter set forth, to be influenced by its movement.

It will be understood that upon magnetic excitation of the core system—e. g., serial excitation of the two pole members 11 and 12—the armature 16 will be attracted to movement toward the gap to effectively shorten the latter, or reduce its reluctance. I arrange the parts so that in respect of one of the pole members (e. g., 11) the movement is toward the member itself (i. e., toward its side 41), the armature upon attraction coming into juxtaposition—i. e., either contact or substantial contact—with the end portion of that side. This effect is obtained by arranging the armature, in direction longitudinal of the envelope, to be co-extensive with a portion of the pole member in question, as well of course as with at least a portion of the gap.

While the armature may bear a similar relationship to the other pole member, or 12, I prefer to arrange it for movement quite closely past the face 22 of that member rather than toward the member, the armature thus being adapted to come into juxtaposition with that face 22. In order that the armature, when of the simple rectangular elevation shown in Figure 1, shall not be prevented by member 11 from coming into such juxtaposition with the face 22, I may provide the pole member 12 with an offset 52 which has the effect of staggering the face 22 with respect to 21, to bring it nearer the center of the envelope. Preferably the degree of this staggering will be such that the armature, when it reaches its gap-ward movement limit of juxtaposition with a portion of the side (e. g. 41) of member 11, will be in substantial alignment or juxtaposition with the face 22 of member 12—expressed in other words, the gap-ward movement of the armature is limited, as by member

11, to an armature position of such substantial alignment or juxtaposition with face 22. In Figure 1 there has of course been illustrated the unattracted or rest position of the armature, wherein it is limitedly biased away from the gap; in this position it is out of alignment with the face 22, preferably being in the particular relationship of partial alignment only. It will be understood that the movement of the armature transverse of the envelope is also a movement transverse of the field across the gap, although this transverse relationship to the gap field may be somewhat oblique in view of the staggering of the faces 21 and 22.

15 For producing the serial magnetic excitation of the core system a coil 34 may be provided around the envelope 1, so that the coil axis is parallel with and near to the pole members 11—12; it will be understood that upon electrical excitation of the coil (as by impressing of a suitable voltage across the coil leads 34a and 34b and consequent current flow through the coil) the pole members will be serially excited in the required manner. Particular features relating to the illustrated coil 34 are hereinafter set forth.

20 I have found the armature and core system as so described to be peculiarly satisfactory in respect of sensitivity to small excitations, and in respect of speed, abruptness and positiveness of action, both at the beginning and ending of armature movement in response to attraction by the core system. I believe that this may result, as well as from other causes, in large measure 25 from at least rough equalization of the forces on the armature in the early and terminal portions of such movement; that this equalization tends to occur as a result of the different member-armature relationships in the respective 30 cases of the two members—the force exerted on the armature by the pole member 11 tending to increase with armature approach to its fully attracted position, and that exerted by the pole member 12 tending simultaneously to decrease; 35 that accordingly the minimum force at any instant during such movement is maintained at a relatively high value for the particular field giving rise to the movement. As to speed, abruptness and positiveness of armature return to 40 the illustrated position (i. e., in response to its bias, upon cessation of the magnetic field), the high sensitivity provides a factor favorable in any particular case to the use of therein relatively strong effective armature bias. It is also 45 to be considered that the permissible small armature size and hence mass contributes significantly to the quick action.

45 I arrange the remainder of the magnetic system of the device to preserve the high sensitivity inherent in the armature and core system, and to heighten the overall efficiency—and in so doing 50 I am able to employ certain members for the joint function of improvement of the magnetic system and of excellent mechanical support and centralization of the elements within the envelope. These members are two spring rings 19 and 20 of magnetic material such as steel, each 55 for example in the form of a leaf spring bent into the shape of the letter "C" (i. e., an almost closed circle), excepting preferably for a small central flattened portion 19a or 20a. Each of these rings 19 and 20 fits snugly and preferably 60 presses against the interior wall of the envelope 1 (excepting in its flattened portion 19a or 20a). 65 Longitudinally they are positioned on opposite

sides of the gap 13; the interior surface of the flattened portion 19a of 19 is secured against the bottom or outer surface of pole member 11, and the interior surface of the flattened portion 20a of ring 20 is secured against the bottom or outer surface of pole member 12. The rings may thus form a significant mechanical support and centralizing means for the pole members or core assembly (to which in turn other internal elements are supported through the insulating stack 10); at the same time they approach closely to the inside of coil 34 at separated longitudinal positions—for example either side of the center, and intermediate the coil extremities—and thus form efficient means for collecting the magnetic field of the coil and passing it through the portion of the core system which includes the gap 13.

While the rings 19 and 20 are useful with a coil 34 of simple design, they are rendered materially more effective if employed with a coil having internal magnetic cylinders extending from the respective coil extremities to overlap the respective rings. This coil structure has been illustrated in the drawing, the magnetic cylinders appearing as 39 and 40. These cylinders desirably fit as closely as practicable over the envelope 1; in turn they preferably fit as closely as practicable within the coil 34—in other words, the coil 34 is formed with an internal dimension just admitting the cylinders. Thus the cylinders lie close to the inside turns of the coil, where the internal field normally tends to be strongest, and therefore efficiently collect the field. They are of course of such length that an appreciable gap 38 is left between them; and this gap being of relatively higher reluctance, the field naturally follows the much lower reluctance circuit from either cylinder through the envelope to the respective collecting ring 19 or 20, through the core system across gap 13, and from the other collecting ring through the envelope to the other cylinder.

In turn still higher efficiency may be obtained by extending the outer extremities of the cylinders 39 and 40 around the coil ends, as by the illustrated cylinder flanges 39a and 40a of magnetic material, and joining them magnetically as by the external cylinder 37 of magnetic material closely fitting the outside of coil 34. This structure collects the external coil field and concentrates it, in its passage internally of the coil, in the desired path above outlined. The complete coil structure amounts to a coil encased in magnetic material excepting for the internal annular gap 38.

It will of course be understood that in the interest of simplicity in the drawing the coil 34 is only fractionally shown, but that it is intended for example to fill the space bounded by 39—39a—37—40a—40.

Attention may now be given to the general organization of the switch of Figures 1 and 2. The spring 17 will be seen to be extended away from the stack 10 for a distance beyond the armature, and to have secured to its bottom surface near its extremity a contact 30. Below this contact 30 is provided a fixed contact 31—for example secured to the top of the pole member 12. The contacts 30 and 31 are normally 70 in slight spaced relationship, forming the normally open switch A. On the top of spring 17 nearer the stack 10—for example above the armature 16—is secured a contact 32; a cooperating contact 33 is provided thereabove to form 75

a switch B. The contact 33 is shown carried on the bottom of a bimetallic arm 9 near one extremity thereof, the arm being clamped at its other extremity in the insulating stack 10. The bimetallic arm 9 is surrounded by a heater winding 9a, of which one extremity is electrically connected with contact 33 (as by connection to the arm 9) and of which the other extremity is connected to a lug 9b clamped in the stack 10. The bimetallic arm 9 and contact 33 form the limiting means for upward movement of the upwardly tensioned spring 17, so that switch B is normally closed. When the arm 9 is heated, however, as by passage of current through the heater winding 9a, the arm moves downwardly, maintaining switch B closed and forcing spring 17 downwardly to close switch A.

Contact 31 is connected with lead-in wire 3, for example through pole member 12, plate 14, pole member 11, and a lug 11a clamped against the pole member 11 and welded to the lead-in wire. With lead-in wire 4 is connected spring 17, and hence contacts 32 and 30. With lead-in wire 5 is connected the lug 9b, and hence, through the heater winding 9a, the contact 33. Thus between lead-in wires 3 and 4 lies electrically the switch A, while between the lead-in wires 4 and 5 lies electrically the serially arranged heater winding and switch B. In Figure 1 there has been schematically indicated as 6 a current source. One terminal 6a of the source 35 is connected with the lead-in wire 5 and with a lead 34a to coil 34. The other terminal 6b of the source is connected through a control switch 7 with lead-in wire 4, while lead-in wire 3 is connected to the other coil lead 34b. Thus the 40 heater winding 9a is connected across the source through the switches 7 and B, while the coil 34 is connected across the source through the switches 7 and A.

When the control switch 7 is closed the heater 45 winding 9a is energized, since switch B is normally closed; this energization heats the arm 9 and the latter moves downwardly. After a predetermined time interval switch A will be closed, the armature 16 by that time having been moved toward but not yet fully into the position it occupies when the magnetic system is energized. But upon closing of switch A, switch 7 of course still being closed, the coil 34 and hence the magnetic system are energized, attracting the armature 16 50 to move an additional distance, and thus flexing the intermediate portion of spring 17 downwardly and opening switch B. This opening of switch B breaks the current flow through the heater winding, so that the arm forthwith begins the process of cooling and restoration to its initial position; but the spring 17 is maintained downwardly, and switch A closed, by the excitation of coil 34, which continues until the control switch 7 is opened.

The completed downward movement of any portion of the spring 17—which after closing of switch 7 is thermally delayed and electromagnetically maintained—may be utilized for any desired purpose and in any desired manner. By way of simple illustration I have shown a load 8 intended to receive current only during the intervals of downward spring position, and have indicated the simple connection of the load in parallel with the coil 34.

The switch so organized presents, over vari-

ous combinations of devices directed to a generally similar purpose, the distinct advantage of extreme simplicity. Broadly this results, among other things, from the electromagnetic means operating directly on the thermally responsive switch A itself, to take over the control of that switch from the thermal element; or, in a slightly different view, from the community of structure and of response to the coil of both switches A and B.

In Figure 1, and in greater detail in the small Figures 3 and 3a, I have illustrated an optional feature particularly for use when the field through the core system is an alternating one—e. g., when the current from the source 6 is alternating. This consists in the use of shading ring means of conductive material surrounding at least one of the pole members 11 and 12, or a portion thereof, near the armature 16; the function of such means will be understood to be the establishment in the core system of a magnetic flux component out-of-phase with the main flux, and accordingly effective to minimize tendencies of the armature to vibrate. With the described arrangements, I have found a particularly effective position for a shading ring to be one surrounding the pole member 11, or preferably a transverse sectional portion thereof, on the opposite side from the gap 13 of the member portion which is longitudinally co-extensive with the armature. Accordingly in the figures in question I have shown the pole member 11 provided with symmetrically disposed longitudinal slots 11a and 11b extending from one side of the member to the other and away from the face 21 for a substantial distance, and dividing the end portion of the pole into three legs 11', 11'' and 11''', and the face 21 into the three portions 21', 21'', 21'''. Around the center leg 11'' the conductive shading ring 43, for example of copper, is slipped to a position slightly beyond the member portion longitudinally co-extensive with the armature, the plate 14 being suitably apertured as at 14a to be secured to pole member 11 after placement of the shading ring in its described position.

While in Figures 1 and 2 I have shown a switch thermally thrown and electromagnetically maintained in thrown position, it will be understood that there is intended no limitation to such a switch of special features of my invention—such for example as the several improvements in the magnetic system. Thus in Figures 4 and 5 I have shown, in a switch arranged to be both thrown and maintained thrown electromagnetically, a magnetic system generally similar to that of Figures 1 and 2. To show, however, that the broader described relationships of armature to core system are not limited to the particular arrangement of Figure 1, I have illustrated in Figures 4 and 5 a modified arrangement wherein those relationships still obtain.

In Figures 4 and 5 the envelope, lead-in wires, and external magnetic structure are employed as before. Collector rings 19 and 20 are again employed, the pole members being secured to the ring portions 19a and 20a. But while in the device of Figure 1 I employed staggered pole member faces and a small, elevationally rectangular armature, I have shown in Figure 4 mutually aligned pole member faces and offset armature. In this figure the pole members and their respective portions, the non-magnetic pole-bridging member, the armature and gap have each been designated with a number higher by

100 than in Figure 1; there is no pole member offset such as 52 of Figure 1; the gap is conveniently somewhat longer than that of Figure 1; and the armature, correspondingly longer, is 5 provided with an offset 153, so that there will be maintained relationships of armature to upper side (e. g., 141) of the one pole, and of armature to face (e. g., 122) of the other pole, similar to the corresponding relationships in Figure 1.

In either of the arrangements of Figures 1 and 4 that pole member with a side portion of which the armature is longitudinally co-extensive may conveniently form a stop for gap-ward movement of the armature. It is not imperative, however, that the juxtaposition with this side portion into which the armature is attracted be one of intimate contact; and if desired the coming into such intimate contact may be positively obviated as by a thin piece of non-magnetic material interposed between armature and pole side—shown for example in Figure 4 as the thin piece 154 secured to the bottom of the portion of armature 116 which would otherwise come fully into contact with pole side 141.

By way of further typical differences from earlier figures, a modified contact arrangement is shown in Figures 4 and 5. The armature is shown carried on the bottom of a spring 117, similar to spring 17 of Figure 1 but not necessarily extended so far beyond the armature, and in this instance connected to lead-in wire 3. On top of the spring 117, for example immediately opposite the armature, is secured a contact 26. To lead-in wire 4 is electrically connected a rod or strip 23, which is preferably of non-magnetic material but may if desired be somewhat resilient; this is clamped in stack 10 and extends therefrom above spring 117 to a position opposite the contact 26. To this strip 23 at this position is secured a contact 27, against which contact 26 may bear when the armature 16 is unattracted and spring 117 obeys its bias; the strip 23 and contact 27 may thus form the means for restricting movement of the armature away from the gap. To lead-in wire 5 may be electrically connected a leaf spring 24, preferably of non-magnetic material, which is clamped in stack 10 and extends above strip 23 to oppose the extremity of spring 117. A rod or spacer 25 of insulating material is secured to this spring 24 near its extremity to extend therefrom into abutment against spring 117 near its extremity; the spring 24 is lightly tensioned oppositely to spring 117—i. e., the two are tensioned toward each other—so that the two springs move in unison, and normally the effective bias on the armature 16 is the relatively more powerful upward spring 117 bias minus the relatively less powerful downward spring 24 bias. To the strip 23, for example above contact 27, is secured another contact 28, and to the spring 24 above the contact 28 another contact 29; the mutual spacing of contacts 28 and 29 is such that upon attraction of the armature to gap-ward movement these two contacts will touch each other just before that movement is completed. Contacts 26 and 27 may be considered as forming a normally closed switch section C connected across lead-in wires 3 and 4, and contacts 28 and 29 as forming a normally open switch section D connected across lead-in wires 4 and 5.

A purely typical circuit is illustrated in connection with the device of Figure 4. The cur-

rent source 6 has been shown connected to a load 8c through the switch section C and to a load 8d through the switch section D, the two switch sections being portions of a single-pole, double throw switch of which lead-in wire 4 represents the pole and lead-in wires 3 and 5 the respective throw contacts; the coil 34 is connected to the current source through the control switch 7. When the switch 7 is closed the core system is magnetically energized and the armature 116 is attracted into juxtaposition with the top side 141 of pole member 111 and with the end face 122 of the pole member 112, opening the switch section C and closing the switch section D (this amounting to a throwing of the entire single-pole, double-throw switch). The thrown positions will of course be maintained as a result of the continued magnetic energization of the core system until opening of switch 7. By reason of the tendencies toward equalization of forces throughout armature movement, and of other characteristics of the improved armature-core system relationships above discussed, both the opening of switch C and closing of switch D (in early and terminal portions of the armature movement, respectively) occur rapidly, abruptly and positively.

In Figures 6-7 I show a device and system similar to that of Figure 1, excepting that there is employed therein an armature which, instead of having different relationships to the two respective pole members, may have similar relationships to the two—e. g., may be arranged for movement into juxtaposition with portions of the top sides of both pole members. The armature, gap and two pole members have been indicated as 216, 213, 211—212 respectively. The pole member 211, secure with the stack 10 and the ring portion 19a, may be formed with an offset 251 toward the armature; the pole member 212, secure with the ring portion 20b, may be formed with the like offset 252. The mutually exposed end faces 221 and 222 of the pole members may be aligned with each other and separated by the gap 213; a non-magnetic plate 214 may bridge the gap, secured to both pole members. In a longitudinal direction the armature 216, carried by the spring 17, may be centralized over the gap; but in this case the armature extends not only over the gap but also to some extent over portions of the top sides (241 and 242) of both the pole members. Normally the armature is limitedly biased away from the gap as before; but it is now adapted to be moved by arm 9 toward a position of juxtaposition with portions of the sides (241, 242) of both the pole members, and by the attraction of the magnetic circuit fully into such a position.

It will be understood that in respect of the thermal device which closes the switch A in either Figure 1 or 6 there is no necessary limitation to a bimetallic strip such as 8, as obviously other thermal devices may be employed. It is also to be understood that while the device has been shown as an electro-thermal one—i. e., heated by an electric current—this is not essential for certain purposes. Thus the heater winding 9a and connections thereto may be omitted, or equivalently the switch 7' (shown in series with lead-in wire 5 in Figure 6) opened; the system will then function, assuming switch 7 closed, to close switch A and keep it closed when and after the thermal element (e. g., bimetallic arm 9) has been heated to a predetermined tem-

perature by any means, such as ambient temperature.

While I have illustrated and described my invention in terms of particular embodiments thereof, it is to be understood that I intend no unnecessary limitations by virtue of the details of those embodiments, which may obviously be varied within wide limits without departure from the spirit of my invention; rather I intend to express the scope of the invention in the following claims, as broadly as the state of the art will permit. No claims, however, are made herein to the arrangements of the switch contacts to form switches A and B or C and D, or to the connectors of those switches or to their operation or their functions, including the operation of thermally throwing and electromagnetic maintaining one or more of them—this and allied subject matter having been disclosed and claimed in my copending application Serial No. 325,935, filed March 26th, 1940, as a division of the instant application.

I claim:

1. A magnetic switch system having two pole members arranged with a gap therebetween for serial magnetic excitation; and a switch-influencing armature supported near said gap for movement transverse of the gap field toward one said member, and co-extensive normally to said movement with portions of said gap and of said one member only.
2. A magnetic switch system having two pole members arranged for serial magnetic excitation, the faces of the respective said members nearest each other forming a gap; and a switch-influencing armature supported for movement into juxtaposition with the side of a first said member and with said face of the second member, and limitedly biased away from said position.
3. A magnetic switch system having two pole members arranged for serial magnetic excitation, the faces of the respective said members nearest each other being staggered and forming a gap; and a switch-influencing armature supported for movement into juxtaposition with the side of a first said member and with said face of the second member, and limitedly biased away from said position.
4. A magnetic switch system having two pole members arranged for serial magnetic excitation, the faces of the respective said members nearest each other forming a gap; a switch-influencing armature supported for movement toward the side of a first said member and past said face of the second member; and means for restricting said armature movement to a position of substantial alignment with said second member face.
5. A magnetic switch system having two pole members arranged for serial magnetic excitation, the faces of the respective said members nearest each other forming a gap; and a switch-influencing armature supported for movement toward the side of a first said member and past said face of the second member, said first member forming a means for restricting said movement to an armature position of substantial alignment with said second member face.
6. A magnetic switch system having two pole members arranged for serial magnetic excitation, the faces of the respective said members nearest each other forming a gap; and a switch-influencing armature supported in spaced relation to the side of a first said member only and out of alignment with said face of the second member, and movable toward said first member side and simul-

taneously into substantial alignment with said second member face.

7. A magnetic switch system having two pole members arranged for serial magnetic excitation, the faces of the respective said members nearest each other forming a gap; and a switch-influencing armature supported in spaced relation to the side of a first said member only and in partial alignment only with said face of the second member, and movable toward said first member side and simultaneously into substantial alignment with said second member face.

8. In a switch system including an evacuated envelope: a magnetically influenced switch including mutually spaced pole members within said envelope, and resilient field collectors respectively associated with said pole members and resiliently fitting against the internal wall of said envelope.

9. In a switch system including an evacuated envelope: a magnetically influenced switch including mutually spaced pole members within said envelope, and thin, substantially cylindrical field collectors respectively associated with said

25 pole members and substantially fitting against the internal wall of said envelope.

10. In a switch system including an evacuated envelope: a switch and a magnetic circuit influencing said switch, within said envelope; mutually spaced internal field collectors forming terminals of said internal magnetic circuit and positioned adjacent the interior wall of said envelope; external field collecting cylinders of magnetic material surrounding said envelope opposite said internal collectors respectively; and a coil surrounding said external field collecting cylinders.

15 11. In a switch system including an evacuated envelope: a switch and a magnetic circuit influencing said switch, within said envelope; mutually spaced internal field collectors forming terminals of said internal magnetic circuit and positioned adjacent the interior wall of said envelope; external field collecting cylinders of magnetic material surrounding said envelope opposite said internal collectors respectively; a coil surrounding said external field collecting cylinders; and means substantially joining said collecting cylinders magnetically around said coil.

20 HERBERT O. WILSON.
